CONCRETE BLOCK

John A. Wilnau, P.O. Box 13026A, Pinecastle Station,
Orlando, Fla. 32809

Filed Oct. 16, 1972, Ser. No. 297,969

Term of patent 14 years

Int. Cl. D25—01

U.S. Cl. D18—2 R

Fig. 1.

Fig. 2.

Fig. 3.

Fig. 4.

FIG. 1 is a perspective view of a concrete block showing my design.

FIG. 2 is an end plan view of the block of FIG. 1;

FIG. 3 is a side plan view of the block of FIG. 1;

FIG. 4 is a second end plan view of the block of FIG. 1. The opposite sides of the block as illustrated in FIGS. 2, 3 and 4 are identical to the side shown.

I claim:

The ornamental design for a concrete block, substantially as shown and described.
